MELTING AND CASTING OF METALS

Neil Douglas Gordon Robertson, Bushey Heath, Essex and Essexshire, England, and Eric Crisp Lewis, Putney, London, England, Essex, Essexshire, England, assignors to Magnesium Elektron Limited, London, England, a British company

Application October 11, 1939, Serial No. 299,014

In Great Britain October 20, 1938

2 Claims. (Cl. 22—79)

This invention relates to the melting and casting of metals.

According to the invention the apparatus comprises a crucible adapted to contain molten metal and gas under pressure, and having a delivery pipe adapted to extend below the level of the molten metal, its upper end being outside the crucible for delivery of molten metal, a device containing gas, preferably inert to the molten metal and connected by a pipe to the interior of the crucible and having relatively movable walls and means for moving said walls towards each other to generate the required gas pressure (without other means for supplying gas under pressure) which is transmitted to the crucible thereby expelling molten metal through the delivery pipe and for moving said walls apart to reduce said pressure, thereby stopping the outflow of metal through the delivery pipe and returning the metal in the delivery pipe to a required level, there being no outlet in the gas system during use through which any appreciable loss of the gas could normally occur. The atmosphere or gas within the vessel will be selected according to the requirements of the metal concerned. If magnesium or a magnesium base alloy, or an aluminium base alloy containing a proportion of magnesium, is being treated, the atmosphere in the vessel may be sulphur dioxide or hydrogen or hydrogen sulphide or other gases inert or comparatively inert to magnesium, or mixtures of such gases, or air and sulphur powder, may be used. For copper or other metals the atmosphere will be suitably chosen and will usually be inert to the metal under treatment. It is very desirable, however, that gases which are appreciably soluble in the melt should not be employed or porosity of the final castings may result. The gas employed, furthermore, may be chosen with a view to effecting a de-oxidation of the molten metal, e. g. hydrogen or carbon-monoxide.

When treating magnesium or alloys containing magnesium the metal may be first purified by usual flux methods or may be purified by flux introduced into the crucible itself. If large scrap (such as foundry runners and risers) or ingot is to be introduced into the crucible it may be first treated to remove surface impurities, e. g. by sand blasting. If flux is to be introduced into the crucible this may be of the very fluid nature or of normally or more than normally inspissated nature, or a fluid flux may be used first and then inspissated later, but the

flux will not necessarily be for the purpose of protecting the magnesium from oxidation, and may be dispensed with altogether. The vessel may be a crucible for normal foundry work, or may be of the large type suitable for magnesium production or alloying purposes. The expelled metal may be received directly into a ladle for casting or into a mould for sand or permanent mould casting, or may enter a pressure chamber for injection into a mould of a pressure die-casting machine or directly into the mould of such a machine.

The delivery pipe is preferably constantly open to the molten metal beneath the upper surface thereof and is of such increasing diameter with in the crucible from its upper end downwards as to prevent jamming should metal become solidified therein, and to render removal of solidified metal an easy matter.

In order that the above described and other features of the invention may be more easily understood a constructional form of the invention will now be described by way of example with reference to the accompanying diagrammatic drawings, wherein:

Figure 1 is a vertical sectional view of an apparatus made in accordance with the invention; and

Figure 2 illustrates a modification to be described.

A crucible 3 mounted in a furnace 4 is formed from iron, steel, or other suitable material or alloy, of inverted dome-shape and without openings therein except of course its open upper end. The crucible is provided with an outwardly directed flange 5 around its upper end or mouth for the reception of a cover or lid 6 in a gas-tight manner. The lid is formed with one or more openings 7 through which the metal can be introduced into the crucible, and each of which is closeable by a cover or cap 8 secured in position in any suitable manner as by a screw clamp 9 or lever action. One or more of the covers 8 can be replaced by a flat cover 10 through which the delivery pipe 11 for the molten metal passes; this pipe can be carried by the cover. The delivery pipe at its outside end may be vertical or inclined and may have a downwardly inclined extension 12 in the form of a trough at its end. The inside part of the delivery tube is of constantly increasing diameter downwardly to prevent freezing of metal therein or to facilitate freeing of metal if it should solidify therein. Its lower end may be within an inch or two of the

bottom of the crucible or may be higher to avoid picking up any sediment, and may conveniently be six inches in diameter at its lower end, and say an inch in diameter at its upper end, according to requirements. The lower end of the pipe is constantly open to receive molten metal. The inner surface of the delivery pipe is unbroken by any valve device and presents a continuous surface from its lower inlet end to its outlet or delivery end. The openings 1 are large enough to permit withdrawal of the delivery pipes therethrough.

Passing through the cover 6 is a gas tube 15. The gas in the crucible tends to escape when the metal charging opening is opened and thus substantially prevents ingress of air. The gas tube is connected to a chamber 16 having relatively movable walls, e. g. a bellows (as shown) or piston and cylinder, which walls can be moved towards or away from each other by hand or power to produce negative, zero, or positive pressure within the crucible, variable at will. This chamber will not necessarily require to be in communication with a supply of gas under pressure, and as shown receives gas through a pipe 17 and non-return valve 18. In the example illustrated the bellows is contained in a metal jacket 19 and the top plate 20 of the bellows carries an upwardly extending toothed rack 21 with which a splined shaft 22 gears, this shaft having a handle 23 whereby the operator can move the walls of the bellows towards each other or apart for increasing or decreasing the pressure of gas in the crucible without loss of gas. The operator will apply a slight positive pressure to eject metal and will reduce the pressure to stop the flow and enable the level of metal to fall in the delivery pipe. When the pressure in the bellows is below atmospheric pressure, the non-return valve situated in the bellows' inlet pipe opens and inert gas or a mixture of sulphur dust and air, etc., is drawn into the bellows. Immediately the pressure rises above atmospheric the non-return valve closes and pressure is built up in the crucible. The pressure used for ejecting the metal preferably is less than say 5 lbs. per square inch and may be only about $\frac{1}{2}$ lb. with very fluid metal. No valve or other means for permitting escape of the gas from the crucible to the atmosphere is required since the gas in the chamber can be used continuously. A cock or blow off valve may be provided in the gas pipe 15. This chamber may be connected to two or more such crucibles through the medium of a distributing cock if desired.

In employing the apparatus a charge of metal or alloy, such for example as magnesium, magnesium alloy, aluminium alloy or copper alloy, is placed within the crucible through the charging door melted, cleaned and if necessary refined, and the door is closed. The dies or moulds may be arranged upon a platform or secured in position in any convenient manner with their "feeders" or "runners" adjacent to the delivery pipe. Pressure may then be increased in the chamber to raise the internal pressure to a convenient amount to expel the metal into the dies or moulds.

In the modification shown in Figure 2 the outlet end 25 of the delivery pipe is shaped to receive a nozzle 26 on the bottom of a ladle 28 so that no metal will be left to solidify in this opening. For this purpose the ladle may have such a nozzle at the lower part thereof corresponding in shape to the shape of the outlet opening. The interior of this nozzle may also be of frusto-

conical shape to receive a ball on the lower end of a vertical rod. The ball serves as a valve to prevent egress of metal but will be pushed upwardly by the metal received from the crucible. The rod may carry a circular or dished plate to prevent the incoming metal from spouting too far upwardly. The ladle may be lagged and provided with a cover plate. The ladle may be placed in a supporting frame when not in use. These details of the ladle are not illustrated as they are well known in the foundry industry.

The crucible may be maintained in the furnace for long periods, thus reducing heat losses, and may be fitted with a pyrometer, safety valve, and other desired parts. Two or more crucibles may be used so that a supply of metal can be arranged always to be available in at least one of them.

We claim:

1. An apparatus comprising a crucible adapted to contain molten metal and gas under pressure, a delivery conduit adapted to extend below the level of the molten metal and having its upper end outside the crucible for the delivery of molten metal, a device containing gas and having relatively movable walls, a pipe connecting such device to the interior of the crucible and constructed to enable the flow of gas between the device and the crucible to occur in either direction along the pipe at any moment, the said device, pipe and crucible forming a gas system, means for moving such walls towards each other to generate the required gas pressure which is transmitted along said pipe to the crucible thereby expelling the molten metal through the delivery conduit and for moving said walls apart whereby said pressure is reduced thereby stopping the outflow of metal through the delivery conduit and returning the metal in the delivery conduit to a required level, there being no outlet in the gas system during use through which any appreciable loss of the gas could normally occur, an inlet for gas to the said system, and an automatically operating return valve controlling said inlet and permitting gas to enter said system if the gas pressure in said system falls below a predetermined degree.

2. An apparatus comprising a crucible adapted to contain molten metal and gas under pressure, a delivery conduit comprising a pipe adapted to extend below the level of the molten metal and having its upper end outside of the crucible for delivery of molten metal, the conduit being constantly open to the molten metal beneath the upper surface thereof and of such increasing diameter within the crucible from its upper end downwards as to enable solidification of the metal therein to be avoided, means whereby said pipe is normally held in position in relation to the crucible and whereby the delivery pipe can be readily removed from the crucible for cleaning, a device containing gas and having relatively movable walls, a pipe connecting such device to the interior of the crucible and constructed to enable the flow of gas between the device and the crucible to occur in either direction along the pipe at any moment, the said device, pipe and crucible forming a gas system, hand operable means for moving such walls by mechanical connections towards each other to generate the required gas pressure which is transmitted along said pipe to the crucible thereby expelling the molten metal through the delivery conduit and for moving said walls apart whereby said pressure is reduced thereby stopping the outflow of metal through the delivery conduit and return-

ing the metal in the delivery conduit to a required level, there being no outlet in the gas system during use through which any appreciable loss of the gas could normally occur, an inlet for gas to the said system, and an automatically operating return valve controlling said inlet and per-

mitting gas to enter said system if the gas pressure in said system falls below a predetermined degree.
